CUTTING DIE FOR ORNAMENTING SHOE-
UPPER PARTS

Stig E. Rosenberg, Brockton, Mass.

Application January 25, 1937, Serial No. 122,095

14 Claims. (Cl. 164—93)

This invention relates to cutting dies for use in cutting an ornamental edge on shoe-upper parts such as vamps or wing tips. The invention includes improvements in cutting and punching dies such as that illustrated and described in the U. S. patent to Brock, No. 1,772,335. Vamps and wing tips for shoes customarily consist of pieces of leather having a U-shape, the inner edge being the one which shows on the finished shoe. Hence, the inner edge of the U is usually ornamented before the piece is stitched to the other pieces to form a shoe upper. This inner edge is bell-shaped, the upper end of the bell being toward the toe of the shoe when the vamp or wing tip is incorporated in a shoe. In general, the shape of the inner edge of a vamp or wing tip varies somewhat for different sizes or widths of shoes.

It is an object of the present invention to provide a cutting die which is adjustable to cut ornamental edges on vamps or wing tips for shoes of different sizes and of correspondingly different widths.

The invention also relates to dies which, in addition to cutting an ornamental edge, also punch one or more rows of holes near the ornamental edge, these holes serving to add to the ornamentation of the part. For regularity of design, the holes in any such row are usually spaced apart uniformly. In the case of vamps, the upper end of the bell shape formed by the inner edge of the vamp may be widened or narrowed for shoes of different widths. According to the invention, means may be provided to adjust the spacing of the punched holes adjacent to the upper end of the bell so as to maintain such spacing approximately uniform when the width of the upper end of the bell is increased or diminished.

For a more complete understanding of the invention, reference may be had to the following description thereof and to the drawings of which—

Figure 1 is a plan view of a cutting die embodying the invention.

Figure 2 is a plan view of the same, showing the parts in different positions.

Figure 3 is a section on the line 3—3 of Figure 1.

Figure 4 is a section on the line 4—4 of Figure 1.

Figure 5 is a section on the line 5—5 of Figure 2.

Figure 6 is a section on the line 6—6 of Figure 3.

Figure 7 is a plan view of two wing tips of dif-

ferent sizes, superimposed on each other to show the different contours of the ornamented edges.

Figure 8 is a plan view of a modified form of the invention.

Figure 9 is a fragmentary plan view of the die shown in Figure 8, the parts being in different positions.

Figure 10 is a section on the line 10—10 of Figure 9.

Figure 11 is a section on the line 11—11 of Figure 8.

Figure 12 is a plan view of another modified form of the invention.

Figure 13 is a fragmentary plan view of a portion of the die shown in Figure 12, on a larger scale.

Figure 14 is a section on the line 14—14 of Figure 13.

The cutting die illustrated in Figures 1 to 6 inclusive may comprise a base 20 on which are mounted a number of blocks 22, 24, 26, 28 and 30. In the embodiment illustrated, the block 22 is fixed. The blocks 24 and 28 are pivotally attached to the block 22 as at pivot points 32 and 34 respectively. The blocks 26 and 30 are pivotally attached to the blocks 24 and 28 respectively at their pivot points 36 and 38. Thus, while the block 22 is immovable with respect to the base 20, the other blocks are slideable on the base and swing about their respective pivot points. Each of the blocks is provided with a groove to receive and confine a portion of a flexible blade 40 which, as indicated in Figure 1, is shaped to the configuration of the ornamental edge which is to be cut on a shoe-upper part such as a wing tip or vamp. Cooperating with the block 22 is a smaller fixed block 42, these blocks alternating the mid-portion of the blade 40. Adjacent to this mid-portion of the blade are two portions which are supported and confined by the blocks 24 and 28 respectively. The end portions of the blade 40 are supported and confined by the blocks 26 and 30 respectively. Thus, the shape of the blade, and hence the shape of the cut made by the blade, is determined by the positions of the movable blocks on the base, the natural shape of the blade being modified by movements of the movable blocks.

The cutting die illustrated in Figure 1 is intended for cutting wing tips for shoes. Wing tips are customarily made by cutting out U-shaped pieces from skins or hides, such pieces having a shape similar to that shown in Figure 7. The outer margin of this piece of leather is to be lasted over the edge of the last when the upper is

pulled over the last in the making of a shoe. The inner edge of the leather piece is the one which appears in the finished shoe. This edge, therefore, is the one which is given an ornamental cut 5 so as to decorate the finished shoe. This ornamental cut, as is evident from Figure 7, is in the shape of a bell, the top of the bell being toward the toe or forepart of the shoe. In cutting wing tips for shoes of different sizes and widths, the 10 arms of the U are made longer for shoes of larger sizes than for shoes of smaller sizes. Furthermore, for shoes of greater widths, the spacing between the arms of the U is greater than for shoes of lesser widths. While shoes of each size 15 may be made in a variety of widths, in the great majority of shoes the larger sizes also have greater widths, so that as a general rule the wing tips having the longer arms also have a greater spacing between the arms. This relationship is 20 clearly illustrated in Figure 7 wherein a pair of wing tips are superimposed so that the outlines of the ornamental edges can be directly compared. As shown, a wing tip 44 for a relatively large sized shoe overlies a wing tip 46 for a smaller 25 sized shoe. The arms of the U-shaped piece of leather forming the larger wing tip 44 are longer and more widely spaced than the arms of the U-shaped piece of leather forming the wing tip 46. These two changes in the contour are 30 made possible by the arrangement of the movable blocks shown in Figure 1. Any suitable means for adjusting the positions of the movable blocks may be employed. As shown, a pair of toggle arms 50 and 52 are employed for adjustably moving the blocks 24 and 28 in their pivots. A second 35 pair of toggle arms 54 and 56 are employed for adjustably moving the blocks 26 and 30. The arms 50 and 52 are pivotally attached to a nut 60 through which is threaded a portion 62 of a rotatable shaft. The arms 54 and 56 are pivotally attached to a nut 66 through which is threaded a portion 68 of the same shaft. This shaft may be rotated by a knurled finger-piece 70 and 40 may be held against axial movement as by a notched plate 72 which fits between a flange 74 and the forward end of the finger-piece 70. In order to obtain the desired relative rates of 45 adjustive movement of the various pairs of blocks, the screw thread of the shaft portion 62 is different from the screw thread of the shaft portion 68, the former having a smaller pitch. Thus, as the shaft is rotated to move the blocks, the nut 60 advances more slowly than the nut 66. The rate of adjustive movement of the various blocks 50 is also determined by the lengths of the toggle arms, the arms 50 and 52 being shorter than the arms 54 and 56. These various members are so 55 designed that, as the blocks 24 and 28 swing toward each other, the blocks 26 and 30 swing away from each other, these relative movements producing the outlines shown in Figure 7. Figure 60 1 shows the movable blocks in position to cut a wing tip for a shoe of large size. Figure 2 shows the parts in position for cutting a wing tip of smaller size. The blocks 26 and 30 may be provided with suitable slots 78 and 80 in which ride screws 82 and 84 respectively which limit the movement of the blocks in either direction. The screws 82 and 84 are mounted in the base 20. 65

70 In addition to cutting an ornamental edge on the wing tip by means of the knife 40, it may be desired to ornament the marginal portion of the wing tip adjacent to the edge by a pattern of punched holes. To this end, a suitable number 75 of punches 90 may be mounted on the various

blocks which support portions of the knife 40. Thus, when the portions of the knife are adjustably moved with the respective supporting blocks, the corresponding punches 90 are also moved by the same amounts. The pattern of the punched 5 holes in the mid-portion of the wing tip may include a group of holes made by punches mounted on a movable block 92. As shown, this block is 10 slideable on the base 20, and, as indicated in Figure 3, is connected as by a bar 94 to the nut 60, so that, when the nut 60 is moved in one direction or the other, the block 92 is correspondingly shifted.

Each of the blocks is preferably provided with a stripper plate 100, these plates being supported 15 in the usual manner by posts 102 having their lower ends resting on springs 104 so that the plates may give when pressure is brought to bear against the work from above.

Figures 8 to 11 inclusive illustrate a modified 20 form of the invention particularly designed for cutting ornamental edges on vamps. These cuts are bell-shaped and vary in width according to the width of the shoes for which they are intended. As indicated in Figure 8, the die 25 includes a base 110 on which are mounted a pair of slideable blocks 112 and 114. These blocks are guided by a guide rail 116 so that they slide toward or from each other. Each block has a slot 118 in which rides a stationary screw 120 to limit 30 the travel of the blocks. In addition to the blocks 112 and 114 which slide toward and from each other, pivotally attached blocks 122 and 124 are provided, the block 122 being pivoted to the block 112 as at 126, the block 124 being pivoted 35 to the block 114 as at 128. Additional pivoted blocks 130 and 132 may also be provided, these blocks being pivoted respectively to the blocks 122 and 124 at the points 134 and 136. Each of the six blocks thus far described is provided with 40 a slot in which a portion of a flexible knife 140 is supported and confined, the adjusted shape of the knife being determined by the positions of the several blocks. The blocks are adjustably moved by any convenient mechanism such as a 45 toggle device 142 operated by a threaded portion 144 of the shaft 146 to move the blocks 112 and 114 toward and away from each other. Another toggle device 150 is operated by a threaded portion 152 of the shaft 146 to swing the blocks 122 50 and 124 about their respective pivots. The swinging movements of the blocks 122 and 124 also cause swinging movements of the blocks 130 and 132 which are pivotally attached thereto, the movement of the latter blocks being influenced 55 by the knife 140 which extends from each block to the next adjacent block and which has a considerable degree of stiffness. A pair of abutment elements 156 and 158 are provided to limit swinging movement of the blocks 130 and 132 in one 60 direction.

As shown, the die may be provided with a series of punches 160 which are mounted on the several blocks and extend in a line following the configuration of the knife 140. As the blocks 65 112 and 114 are adjustably moved away from each other, it is evident that the space between the adjacent end punches on these blocks will increase. In order to avoid an excessive spacing between these adjacent punches, an additional punch may be inserted between them when the blocks 112 and 114 are moved away from each other. This additional punch 162 may be mounted on a carrier 164 as indicated in Figure 10, the carrier being pivoted as at 166 so that 70 75 75

it can be rocked forward to move the punch 162 to an inoperative position. Figure 10 illustrates the punch in its operative position ready for use. Figure 11 shows the punch in its idle position.

5 Figures 12 to 14 inclusive illustrate mechanism by which the uniformity of spacing of the punches can be better preserved during the adjustable movements of the knife-supporting blocks. Figure 12 illustrates a die having a base 170 on which are slidably mounted a pair of blocks 172 and 174, these blocks being movable toward and from each other to vary the width of the forward portion of the bell-shaped cut made by a knife 178 which is supported by the blocks 15 172 and 174, other portions of the knife being supported and confined by swingable blocks 180 and 182, the latter being hinged respectively to the blocks 172 and 174 as at 184 and 186. A number of the punches 190 at the mid-portion of 20 the ornamental edge are individually mounted on lever arms 192, 194 and 196 on the block 172, and 200, 202 and 204 on the block 174. It is obvious that, while three such lever arms are shown on each of the blocks 172 and 174, a greater 25 or lesser number of such arms may be employed as found convenient or necessary. The arms 192, 194 and 196 are pivoted individually as at 210 on the block 172. The arms 200, 202 and 204 are likewise pivoted at the points 216 on the 30 block 174. The arms in each of these groups are connected by plates 220 and 222 respectively. The plate 220 is attached to the three arms of its group at the pivot points 224, 226 and 228 respectively. In like manner, the plate 22 is attached to the arms of its group at the points 230, 232 and 234 respectively. It is thus evident that, if any one arm of either group is rocked about its pivot, the connecting plate will cause 35 the other two arms of the group to rock accordingly, but the actual amount of rocking movement of each arm will differ since the points of attachment of the several arms to the plate are at different distances from the respective rocking axes 210 or 216. The inner two arms 196 and 40 200 are notched at their ends as at 240 and 242. Within these notches are a pair of lugs 244 and 246 respectively. When the blocks 172 and 174, carrying the groups of arms, are adjustably 45 moved away from each other, the arms of one group move away from the arms of the other group. Since the lugs 244 and 246 catch in the notches 240 and 242, the arms 196 and 200 are forced to rock on their respective pivots. This 50 rocking movement of these arms counteracts the tendency to increase the spacing between the punches 190 on these arms. Owing to the connecting plates 220 and 222, the other arms of each group are also forced to rock on their 55 pivots but to lesser extents, these rocking movements also tending to counteract partially the spread effect of the movement of the blocks on which the arms are mounted. Thus the six punches 190, which are connected on the rock 60 arms, are gradually spread apart so that the spacing between the successive punches carried by these arms is maintained approximately uniform, that is, excessive inequality of spacing is avoided, that being true for any position of adjustment of the blocks 172 and 174.

While the rock arms are shown in connection with a single pair of swinging blocks 180 and 182, it is evident that the same features could be employed with swinging blocks such as are illustrated in Figure 8.

If desired, a suitable scale 250 may be mounted on the base 170 to cooperate with an index 252 on one of the blocks to indicate the size of shoe corresponding to the particular adjustment of the blocks of the die.

It is evident that various modifications and changes may be made in the details of structure shown and described without departing from the spirit or scope of the invention as defined in the following claims.

I claim:—

1. A cutting die comprising a base, a blade having the approximate shape of the cut to be made, a series of blocks on the upper face of said base supporting and confining said blade to determine the shape thereof, means maintaining said blocks against said face, said blocks including a pair slidably on said face and confining portions of said blade symmetrical with respect to its mid-point, said blocks also including a second pair slidably on said face and confining portions of said blade adjacent respectively to said symmetrical portions, and means for adjustably moving said blocks on said base.

2. A cutting die comprising a base, a blade having the approximate shape of the cut to be made, a series of blocks on the upper face of said base supporting and confining said blade to determine the shape thereof, means maintaining said blocks against said face, said blocks including a pair movable on said base and confining portions of said blade symmetrical with respect to its mid-point, said blocks also including a second movable pair pivotally attached respectively to the first said pair and confining portions of said blade adjacent respectively to said symmetrical portions, and means for simultaneously adjusting the positions of all said blocks.

3. A cutting die comprising a base, a flexible blade having the approximate shape of the cut to be made, a series of blocks on said base supporting and confining said blade to determine the shape thereof, said blocks including a pair movable on said base and confining portions of said blade symmetrical with respect to its mid-point, said blocks also including a second pair movable on said base and confining portions of said blade adjacent respectively to said symmetrical portions, and means for simultaneously moving one pair of said blocks toward each other and the other said pair away from each other.

4. A cutting die comprising a base, a flexible blade having the approximate shape of the cut to be made, a series of blocks on said base supporting and confining the blade to determine the shape thereof, said blocks including a pair movable on said base and confining portions of said blade symmetrical with respect to its mid-point, said blocks also including a second pair pivotally attached respectively to said first pair, and means for adjustably moving said blocks on said base.

5. A cutting die comprising a base, a flexible blade having the approximate shape of the cut to be made, a series of blocks on said base supporting and confining the blade to determine the shape thereof, said blocks including a pair movable on said base and confining portions of said blade symmetrical with respect to its mid-point, said blocks also including a second pair pivotally attached respectively to said first pair, and means for simultaneously adjusting the positions of all said blocks.

6. A cutting die comprising a base, a flexible blade having the approximate shape of the cut to be made, a series of blocks on said base sup-
